UNITED STATES PATENT OFFICE.

EUGENE SISSON, OF HUDSON, NEW YORK.

BUTTON-SEWING MACHINE.

1,375,235.

Specification of Letters Patent. Patented Apr. 19, 1921.

Application filed April 12, 1920. Serial No. 373,450.

To all whom it may concern:

Be it known that I, EUGENE Sisson, a citizen of the United States, residing at Hudson, in the county of Columbia and State of New York, have invented new and useful Improvements in Button-Sewing Machines, of which the following is a specification.

Reference may be had to the accompanying drawings, and the reference characters marked thereon, which form a part of this specification. Similar characters refer to similar parts in the several figures therein.

This invention relates to machines for attaching buttons to garments or other articles made of flexible sheet-material; and it relates more particularly to machines for stitching buttons to shirts or other garments.

The principal object of the invention is to facilitate the proper spacing-apart of the buttons as they are attached to the garment or other article.

Other objects will appear in connection with the following description.

Figure 1 of the drawings is a top plan view of the bed-plate or work-plate of a button-sewing machine equipped with the usual button-holding-chuck and with my improved gage.

Fig. 2 is a vertical cross-section of the same taken on the broken line 2-2 in Fig. 1, also showing the needle and the work.

Referring to the drawings wherein the invention is shown in preferred form, 1 is the bed-plate or work-plate of an ordinary button-sewing machine having the usual button-holding chuck, 2, and the usual stitching mechanism for stitching the buttons to shirts or the like.

For the purpose of my invention, the stitching mechanism may be of any known form, and I have therefore not shown the same in detail, but have merely shown the needle, 3, thereof, which is operated to stitch to a shirt-front, 4, or the like, a button, 5, held by the chuck, 2, all in the usual manner. At one side of the button-chuck and stitching mechanism I mount upon the bed-plate 1, or other suitable support, my improved gage, 6, which is provided with a depression or opening, 7, which opening is adapted to receive a depressed portion, 4^a,

of the shirt front, 4, together with a button, 5^a, previously attached thereto, as shown in Fig. 2.

The gage is formed with a slot, 8, and is adjustably secured to the bed-plate, 1, by means of a screw, 9, passing through said slot, whereby the position of the gage can be adjusted from time to time to adapt the machine for the particular kind of work in hand.

The gage is thus adjusted in such a position that the opening, 7, in the gage is at a distance from the button-chuck and stitching mechanism corresponding to the desired distance from one button to a neighboring button on the front, 4, of the shirt.

In the operation of the device, the first of a series of buttons, as the button, 5^a, is first stitched upon the garment at the desired point. The operator then grasps this stitched-on button and the neighboring portion of the garment and slides the garment in the direction of the gage until the button, 5^a, and the immediate portion of the garment to which said button is attached are brought into line with and depressed within the opening, as shown in Fig. 2, in which position they are held depressed by one hand of the operator while the garment is stretched by the other hand of the operator beneath the button-chuck, and is so held while another button, 5, inserted in the chuck is stitched to the garment.

The operation is then repeated by moving the garment and depressing the last-attached button, 5, and the immediate portion of the garment within the opening in the gage.

The successive buttons will thus be accurately spaced apart, each previously attached button being thus caused to cooperate with the gage in determining the proper position for the button to be next attached.

Much difficulty has been found in accurately gaging the distance apart of machine-attached buttons due to the fact that the bed-plate at a point where a gage might be conveniently used is covered by the garment or other work.

My improved gage is therefore particularly adapted for the intended purpose because in its use it is not necessary for the operator to see the gage, but merely by the sense of feeling to locate the opening, 7, and

then depress into the opening the previously attached button with the immediate portion of the garment adjacent thereto.

The form and size of the opening, 7, may 5 be varied to adapt the gage for use with work having buttons of different forms and sizes.

It is not necessary that the opening, 7, should extend entirely through the plate 10 forming the gage, but by having a perforate opening the opening can be readily freed from accumulations of lint or dirt.

I have shown and described the invention in its preferred use for sewing buttons to 15 shirts, but it will be apparent that it can be employed for attaching buttons to flexible sheets of various kinds.

What I claim as new and desire to secure by Letters Patent is—

20 1. In a button-attaching machine, the combination with button-attaching mechanism; of a gage provided with an opening

with an upwardly facing mouth adapted to receive both a depressed portion of a flexible sheet and a button attached thereto, said 25 gage being so located that said opening is at a distance from the button-attaching mechanism corresponding to the desired distance from one button to a neighboring button on said sheet.

2. In a button-sewing machine, the combination with stitch-forming mechanism, and a button-holding chuck; of a gage provided with an upwardly flaring opening 30 adapted to receive both a depressed portion of a flexible sheet and a button attached thereto, said gag being so located that said opening is at a distance from the button-chuck corresponding to the desired distance 35 from one button to a neighboring button on said sheet.

In testimony whereof I have hereunto set my hand this 8th day of April, 1920.

EUGENE SISSON.
